CARTON

James N. Edgeington, Richard G. Odell, and Edgar G. Lowrance II, Albuquerque, N. Mex., assignors to IMS Corporation, Albuquerque, N. Mex.

Filed Nov. 29, 1971, Ser. No. 203,122

Term of patent 14 years

Int. Cl. D9—03

U.S. Cl. D9—224

FIG. 2

FIG. 1 is a top, front perspective view of a carton showing our new design; and

FIG. 2 is a bottom, rear perspective view thereof showing the side not seen in FIG. 1.

The characteristic feature of our design resides in the combination of three circular viewing windows and a recessed bottom on a carton as shown.

We claim:

The ornamental design for a carton, substantially as shown and described.
